CHAIN DISCONNECTOR

Louis C. Banker, 268 E. 1st, Britt, Iowa 50423
 Continuation of application Ser. No. 298,952, July 31, 1963. This application Oct. 24, 1965, Ser. No. 511,279
 2 Claims. (Cl. 59—7)

This invention is a continuation of the applicant's co-pending application No. 298,952, filed July 31, 1963, now abandoned, titled, Chain Disconnector.

This invention relates to chain link removers and more particularly it is an object of this invention to provide a chain link remover of a type using a long power lever for speedy and powerful link removal in which the direction of operative swinging of a free end of the power lever is toward the underside of a base of the disconnector which is substantially adapted to be received upon an operator's knee so that it becomes practical for the elongated swinging lever type of disconnector to be used far from a work bench and at the place of use of the chain itself.

A further object of the invention is to provide a chain disconnector as described, the particular area of the undersurface of the base of which is received on an operator's knee being made approximately smooth so as to be comfortable in use.

A further object is to provide a chain disconnector as described which when rested on an operator's knee allows both of the operator's hand to be free for using maximum pressure in manipulating the lever.

Other and further objects and advantages of the present invention will be apparent from the following detailed description, drawings and claims, the scope of the invention not being limited to the drawings themselves as the drawings are only for the purpose of illustrating a method by which the principles of this invention can be applied.

Other embodiments of the invention utilizing the same or equivalent principles may be used and structural changes may be made as desired by those skilled in the art without departing from the present invention and the purview of the appended claims.

In the drawings:

FIGURE 1 is a side elevational view of the improved chain link disconnector, with a portion of a standard on the near side of the jig broken away.

FIGURE 2 is a plan view of the disconnector also with parts of standards of the jig broken away.

FIGURE 3 is an end elevational view of the chain disconnector with a rack bar in the lower part of the jig shown in section.

In the accompanying drawings, and in the following specification, the same reference characters are used to designate the same parts and elements throughout, and in which the numeral 10 refers to the invention in its entirety, numeral 12 indicating a base plate upon which the parts are mounted, numeral 14 indicating a rack bar having teeth 16 in the upper surface and mounted to slide longitudinally between guides 18 and 20 on the base plate, numerals 22 and 24 indicating vertically disposed standards extended upwardly from the base plate, numeral 26 indicating a handle secured by bolts 28 and 30 to an evener 32, the evener being pivotally mounted by a bolt 34 between the standards 22 and 24, numeral 36 indicating a bar pivotally mounted by a bolt 38 between the uprights and connected, at the upper end, by links 40 and 42, numeral 44 indicating a pawl pivotally mounted by a pin 46 on the bar 36 and positioned to mesh with the teeth 16 of the rack bar 14, numeral 48 indicating an elongated bolt extended through a chain link holder 50 and having a clamp 52 and a wing nut 54 thereon, numerals 56 and 58 indicating stops between which chain

2

links are placed for forcing chain links together, and numeral 60 indicating an adjustable slide for setting the parts to accommodate chains of different sizes.

The inner end of the handle is bifurcated, having arms 62 and 64 that straddle the evener 32, and the evener is provided with spaced openings 66 through which the handle is bolted in adjusted positions on the evener. The upper end of the bar 36 is secured by a bolt 68 to extended ends of the links 40 and 42, and the opposite ends of the links are connected to the evener 32 by a bolt 70. The bolt 34 is provided with spacing sleeves 72 and 74 which hold the evener in the center between the standards. Similar spacing sleeves 76 and 78 are provided on the bolt 38, and the pawl 44 is provided with a trigger or handle 80. The bolts 34 and 38 are retained in position by nuts 82 and 84, respectively.

The chain holder 50 extends upwardly at angle, as shown in FIGURE 3, and a chain, such as the links 86, 88 and 90 are placed in the holder, as shown. The elongated bolt 48 extends through an ear 92 and the end is provided with a nut 94 and the face of the clamp 52 is provided with a shoulder 96 that limits movement of the chain. The face of the clamp is also provided with a horizontally disposed shoulder 98 for supporting the chain.

The threaded rod 48 provides means for opening and closing the chain holder 50, and to disconnect the chain links are placed between the stop 58 and the holder 50 for the top of the holder and chain. The links may also be placed between the stop 58 and the pusher 60, and the rack bar actuated to slide links from the chain. The pusher, or stop 60, is carried by an adjustable slider 100 that is adjusted to compensate for different sizes of chain. The slider is retained in adjusted positions by a set screw 102.

OPERATION

With the parts assembled as illustrated and described a chain, of the detachable link type, is placed across the chain holder, as shown in FIGURE 3, and by turning the wing nut 54, the member 52 is actuated to clamp the chain against the holder 50. By operating the handle 26, the stop or pusher 58 is actuated to force a link of the chain out of its position in the chain, and with this link removed a new link, as indicated by the numeral 86 is positioned between the stops 56 and 58. The handle 26 is then actuated to slide the new link into position in the chain.

It will be understood that the stop 56 may be omitted and the stop 58 used, first to remove a link from the chain, and then to replace the removed link by a new link. The stop 60 is adjustable to compensate for chain of different sizes.

From the foregoing description it is thought to be obvious that a chain disconnector constructed in accordance with my invention is particularly well adapted for use by reason of the convenience and facility with which it may be assembled and operated, and it will also be obvious that my invention is susceptible of some change and modification without departing from the principles and spirit thereof, and for this reason, I do not wish to be understood as limiting myself to the precise arrangement and formation of the several parts herein shown in carrying out my invention in practice, except as claimed.

I claim:

1. A chain link disconnector comprising in combination: a base having on its underside an approximately horizontal supporting surface, an elongated rack bar having teeth in its upper surface slidably mounted on the top of said base, elongated guide means on said base and operatively correlated with sideways movement of said rack bars, a pawl adjacent one end of said rack bar and

mounted to coat with the teeth thereof, an elongated handle extending approximately parallel to said rack bar as seen in top plan view, said handle extending in a direction approximately parallel to said rack bar as seen in side elevation, means operatively connecting said pawl to one end of said handle, the other end of said handle being free, a rack bar chain link receiving means attached to the other end of said rack bar, a base chain link holder attached to said base in a position operatively correlated with said receiving means for holding a link which is adjacent a link of a same chain held by said rack bar link receiving means, said supporting surface of said base being beneath said free end of said handle and being sufficiently close to parallelism with said free end of said handle at times when both are seen in side elevation that an operator resting said supporting surface on his knee

10

5

15

can press said handle toward said supporting surface of said base to cause said pawl to cause movement of said rack bar.

2. The combination of claim 1 in which said supporting part of the underside of said base is approximately smooth so as to be comfortable to an operator when received on an operator's knee when in use.
